(57) **CLAIM**

The ornamental design for a casing of a produce-growing system, as shown and described.

DESCRIPTION

FIG. 1 is a front perspective view of a casing of a produce-growing system;

FIG. 2 is a front view thereof;

FIG. 3 is a back view thereof;

FIG. 4 is a left-side view thereof;

FIG. 5 is a right-side view thereof;

FIG. 6 is a top view thereof; and,

FIG. 7 is a bottom view thereof.

The broken lines in the drawings represent portions of the casing of a produce-growing system and form no part of the claimed design. Portions of the casing of a produce-growing system that do not include shading lines form no part of the claimed design.
